UNITED STATES PATENT OFFICE

EDWARD BRUNHOFF, OF WYOMING, OHIO

DESIGN FOR AN ADVERTISING CHANGE TRAY

Application filed April 20, 1929. Serial No. 30,966. Term of patent 7 years.

To all whom it may concern:

Be it known that I, EDWARD BRUNHOFF, a citizen of the United States, residing at Wyoming, in the county of Hamilton and State of Ohio, have invented a new, original, and ornamental Design for an Advertising Change Tray, of which the following is a specification, reference being had to the accompanying drawings, forming part thereof.

Figure 1 is a perspective view of an advertising change tray, showing my new design, and Figure 2 is a central longitudinal sectional view of Fig. 1.

The essential feature of the invention resides in an opaque base member of substantially rectangular form having rounded corners, and upon which is centrally superimposed a transparent tray having a flange at its base which extends outwardly therefrom and

seats upon the opaque base, the sides of the tray and the flanged base having rounded corners and being of corresponding shape to that of the opaque base. The top of the tray is inclined and the opaque base has a correspondingly inclined central recess so as to receive an article to be displayed and to hold same substantially parallel to the inclined top of the tray, and is combined with four clips of a color contrasting that of the base which latter are of less length than the respective sides of the tray and overlap the flanges thereof, and have their corners rounded to correspond to the rounded corners of the base, of the tray and of the tray flange.

I claim:

The ornamental design for an advertising change tray, as shown and described.

EDWARD BRUNHOFF.
